UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

TRANSFERRING MECHANISM FOR AUTOMATIC FILLING-REPLENISHING LOOMS.

1,395,010.

Specification of Letters Patent.

Patented Oct. 25, 1921.

Application filed August 5, 1920. Serial No. 401,490.

To all whom it may concern:

Be it known that I, ALONZO E. RHOADES, a citizen of the United States, and resident of Hopedale, county of Worcester, State of Massachusetts, have invented an Improvement in Transferring Mechanism for Automatic Filling-Replenishing Looms, of which the following description, in connection with the accompanying drawing, is a specification, like characters on the drawing representing like parts.

This invention relates to improvements in filling replenishing looms in which a supply of filling carriers is maintained in a battery or hopper from which they are transferred successively to the active shuttle by a suitable transferrer, and the principal object of the invention is to provide means for insuring the transfer of a properly positioned filling carrier to the shuttle and to prevent the transfer of an improperly positioned filling carrier and thereby prevent a smash or breakage of parts of the transferring mechanism.

The invention is disclosed herein as applied to an automatic filling replenishing loom of the well known "Northrop" type in which an intermittently rotatable hopper, having a series of peripheral filling carrier supporting recesses, is employed, but it will be understood that the invention may be applied to other types of battery mechanisms for automatic filling replenishing looms.

In the usual hopper mechanism of a "Northrop" type of filling replenishing looms the disk which supports the filling carriers is intermittently rotated to advance the filling carriers to transferring position and when the filling carrier reaches transferring position it engages with an abutment located upon the hopper stand in alinement with the position of the shuttle at the time transferring action takes place. The intermittent rotation of the disk or hopper occasionally is insufficient to place the filling carrier properly in transferring position, and upon other occasions an overthrow of the mechanism for locating the hopper would cause the filling carrier, after engaging the abutment, slightly to rebound and thereby to displace the filling carrier from proper transferring position. In either event the blow of the transferrer upon the improperly positioned carrier is likely to thrust said carrier against a rigid part of

the loom and thereby to cause a smash which sometimes results in the breakage of parts of the loom.

The present invention contemplates the provision of automatically operable means carried by the transferrer which will selectively force a properly positioned filling carrier into the shuttle and which will, upon engagement with an improperly positioned filling carrier, prevent transfer without causing a smash, preferably by rotating the hopper in a retrograde direction.

Other objects and features of the invention will more fully appear from the following description and the accompanying drawings and will be pointed out in the annexed claims.

The drawings illustrate a sufficient portion of a "Northrop" loom of the usual type to show the invention as embodied therein.

In the drawings:

Figure 1 is an end elevation, partly in transverse section, of a sufficient portion of a loom to disclose the application of the invention thereto,

Fig. 2 is an end elevation of the transferrer showing a preferred embodiment of the invention applied thereto,

Fig. 3 is a detail side elevation of a portion of the transfer arm and head showing the filling carrier engaging member pivotally mounted thereon engaging a filling carrier which is in proper transferring position, and,

Fig. 4 is a similar view showing the pivotally mounted filling carrier engaging member engaging an improperly positioned filling carrier.

The loom illustrated in the accompanying drawings is of the usual "Northrop" type comprising a side frame 1 having a breast beam 2 upon which is mounted a hopper stand 3 having a horizontal shaft 4 upon which is mounted the usual rotary disks which support the filling carriers. One of these disks 5 is illustrated herein as having a series of peripheral sockets 6 to receive the filling carriers.

The transferrer is of the usual type comprising an arm 7 which is pivotally mounted upon a transferrer stud 8 projecting from the hopper stand and having at its opposite end a head 9. The transferrer is also provided with a downwardly depending arm 10 upon which is mounted a dagger 11 which is

adapted to be engaged, upon call for transfer, with the usual bunter upon the lay 12 which is supported upon the usual swords 13 and is actuated in any well known manner.

Any suitable type of controlling mechanism may be provided for initiating the action of the transferring mechanism upon breakage of filling, or exhaustion of filling, 10 in the active shuttle.

The hopper disk 5 is provided with an annular ratchet 14 which is engaged by a pawl 15 pivotally mounted upon a stud 16 on the transfer arm, and provided with a suitable 15 stud to engage the teeth of the ratchet 14. Upon the downward movement of the transfer arm, when it is actuated to thrust a filling carrier into the shuttle, the pawl 15 drops from one tooth of the ratchet 14 to the 20 next, and upon upward movement of the transfer arm the disk is rotated one step to bring the leading filling carrier of the series into transferring position, at which time it contacts with an abutment 17 carried by the 25 hopper stand. The hopper, when thus rotated, is locked at each step of rotation by a dog 18 which engages the proper tooth of the ratchet 14. The teeth of the ratchet 14 do not present abrupt shoulders so that the 30 hopper disk may be moved quite readily in either direction by hand.

During the operation of the transferring mechanism the disk some times is not rotated sufficiently to bring the leading filling 35 carrier into transferring position. At other times the hopper disk is rotated so vigorously by the transferring mechanism as to cause the leading filling carrier to rebound upon its engagement with the abutment 17 40 and thus to be improperly positioned relatively to the shuttle. In either instance, the blow of the transfer arm upon said improperly positioned filling carrier is likely to cause a smash, or to break some part of the loom.

By the present invention means have been provided which will automatically insure the transfer of a properly positioned filling carrier to the active shuttle and which will 50 prevent the transfer of an improperly positioned filling carrier.

In the preferred embodiment of the invention disclosed herein the head 9 of the transerrer is provided with a recess having 55 a concave bearing 19, partially cylindrical in form, and having shoulders 20, 21. A filling carrier engaging member 22, having a complementary convex bearing member 23 engaging the concave member 19, is pivotally 60 mounted to swing upon a short radius about a stud 24 which is suitably supported in the lower portion of the head 9 of the transerrer, the stud being held in place by a collar 25, or by any other suitable means.

65 The filling carrier engaging member is

provided with a reentrant, preferably concave, face 26 to engage the base portion of the filling carrier to be transferred. The filling carrier engaging member is also provided with shoulders 27, 28 adapted respectively to engage the shoulders 20, 21 upon the head of the transerrer and thereby to limit the pivotal movement of the filling carrier engaging member. The relation of the coöperating shoulders 20, 27 is such that 70 when, upon the downward movement of the transerrer, the filling carrier engaging member engages a properly positioned carrier, said carrier will be thrust from the hopper directly into the shuttle. When, however, the reentrant or concave face of the filling carrier engaging member comes in contact with an improperly positioned filling carrier, said filling carrier engaging member will be rocked about its pivot 75 until the shoulder 28 engages the shoulder 21 upon the head. Thereupon further downward movement of the transerrer will cause the filling carrier to be forced laterally, and inasmuch as it is held in a recess 6 of the hopper disk 5, the hopper disk will be rotated in a retrograde direction sufficiently to remove the filling carrier from transferring position without discharging it from the disk or hopper. Upon 80 the upward movement of the transerrer the pawl 15 will rotate the hopper disk forwardly and again place the filling carrier in transferring position. If, in the meantime, transfer is again called for by the detecting 85 mechanism of the loom, the transerrer will again be forced downwardly and should the filling carrier be properly positioned this time it will be transferred to the shuttle, but if improperly positioned the action of the 90 filling carrier engaging member will again rotate the disk in a retrograde direction and will continue to do so upon successive action of the transerrer until the loom is automatically stopped in the usual manner.

By reason of this invention, therefore, the transfer of a properly positioned filling carrier to the shuttle is insured and means are provided whereby an improperly positioned filling carrier cannot cause harm to the loom. 105 Furthermore, in many instances, the retrograde movement of the hopper, which is effected by reason of the engagement of the filling carrier engaging member with a filling carrier which is not properly positioned, 110 by reason of insufficient rotation of the hopper disk, or by the rebound of the hopper, will enable the next forward rotation of the hopper disk properly to place the filling carrier in transferring position so that stoppage 115 of the loom is avoided.

It will be understood that the embodiment of the invention disclosed herein is illustrative and not restrictive and that various modifications in form, construction, and ar- 120 125 130

angement of parts may be made within the spirit and scope of the following claims.

Having thus described my invention, what I claim as new, and desire to secure by Letters Patent, is:

1. In an automatic filling replenishing loom comprising a hopper to support a supply of filling carriers, a transerrer for forcing a filling carrier from the hopper into the active shuttle, and means for positioning said filling carriers successively in the path of said transerrer, filling carrier engaging means partaking the movement of said transerrer automatically operable upon actuation 10 of the transerrer selectively to force a properly positioned filling carrier from the hopper into the shuttle and to remove an improperly positioned filling carrier from transferring position.
2. In an automatic filling replenishing loom comprising a hopper to support a supply of filling carriers, a transerrer for forcing a filling carrier from the hopper into the active shuttle, and means for positioning 15 said filling carriers successively in the path of said transerrer, filling carrier engaging means pivotally mounted upon said transerrer to swing upon a short radius and automatically operable selectively to force a properly positioned filling carrier from the hopper into the shuttle and to remove an improperly positioned filling carrier from transferring position.
3. In an automatic filling replenishing 20 loom comprising a hopper to support a supply of filling carriers, a transerrer for forcing a filling carrier from the hopper into the active shuttle, and means for positioning said filling carriers successively in the path 25 of said transerrer, means pivotally mounted on said transerrer to swing upon a short radius having a reentrant face adapted to engage a filling carrier upon actuation of said transerrer, and means for limiting the 30 pivotal movement of said filling carrier engaging means in either direction to cause the same selectively to force a properly positioned filling carrier from the hopper into the shuttle and to prevent transfer of an 35 improperly positioned filling carrier.
4. In an automatic filling replenishing 40 loom comprising a rotary hopper having means for supporting a series of filling carriers, a transerrer having a head, means for rotating said hopper to position the filling carriers successively in the path of said transerrer, filling carrier engaging means carried by said transerrer head and automatically operable upon actuation of said 45 transerrer selectively to force a properly positioned filling carrier from the hopper into the shuttle and upon engagement with

an improperly positioned carrier to rotate said hopper in a retrograde direction and thereby to prevent transfer of said filling 55 carrier.

5. In an automatic filling replenishing loom comprising a rotary hopper having means for supporting a series of filling carriers, means for rotating said hopper to 60 present said filling carriers successively in transferring position, a pivotally mounted transerrer having a head a member presenting a reentrant face to engage a positioned filling carrier pivotally mounted on said head to swing upon a short radius and operable upon actuation of said transerrer selectively to force a properly positioned filling carrier from the hopper into the shuttle and upon engagement with an improperly 65 positioned filling carrier to rotate said hopper in a retrograde direction and thereby to prevent transfer.

6. In an automatic filling replenishing loom comprising a rotary hopper having 70 means for supporting a series of filling carriers, means for rotating said hopper to present said filling carriers successively in transferring position, a pivotally mounted transerrer having a head provided with a 75 cylindrical, concave bearing, a member having a complementary cylindrical bearing engaging said seat pivotally mounted on said head and provided with a reentrant face to engage a positioned filling carrier, means for 80 limiting the pivotal movement of said filling carrier engaging member to cause the same when in engagement with a properly positioned filling carrier to force said filling carrier into the shuttle and when in engagement with an improperly positioned filling carrier to rotate said hopper in a retrograde 85 direction and thereby prevent transfer.

7. A transfer arm for automatic filling replenishing looms comprising a head a filling carrier engaging member presenting a reentrant face to engage the filling carrier pivotally mounted on said head to swing upon a short radius, and means for limiting the pivotal movement of said filling carrier 90 engaging member.

8. A transfer arm for automatic filling replenishing looms comprising a head a filling carrier engaging member presenting a reentrant face to engage the filling carrier pivotally mounted on said head to swing upon a short radius, said head and filling carrier engaging member having coöperating shoulders for limiting the pivotal movement of said filling carrier engaging member.

In testimony whereof, I have signed my name to this specification.

ALONZO E. RHOADES.
